UNITED STATES PATENT OFFICE.

HELMUT SELL, OF BERLIN-SIEMENSSTADT, GERMANY, ASSIGNOR TO SIEMENS & HALSKE, AKTIENGESELLSCHAFT, OF SIEMENSSTADT, GERMANY, A CORPORATION OF GERMANY.

MICROPHONIC RELAY.

Application filed May 6, 1925, Serial No. 28,447, and in Germany September 13, 1924.

The present invention relates to improvements in microphonic relays in which the input currents energize an electro-magnetic system by means of which a microphone 5 diaphragm is oscillated. By the formerly known amplifying relays of this kind the transmitted oscillations especially those of voice frequency are more or less distorted.

The object of the invention is to avoid 10 this drawback by transmitting the received current in a more exact manner than formerly known. The invention is especially suited for devices for which the vacuum tube amplifiers—which recently have replaced 15 the microphone amplifiers for most purposes—are not suited. This is for instance the case in hearing apparatuses for the deaf, where the entire outfit is carried by the person using it and which must therefore be 20 of a simple construction as the individuals using the same are unskilled persons. Also for radio apparatuses it is important that the elements are simple and easily operated, so that the microphone is especially suited 25 for use also in radio outfits.

In the formerly known microphone amplifiers the distortion of the voice oscillations are partly due to the microphone contact and partly to the oscillating element acting 30 upon the contact, which element, while in most cases of diaphragm shape was heretofore designed on incorrect principles.

According to the invention an essential improvement in the known arrangements is obtained by using as a microphone diaphragm a metal foil which is radially stretched and which is oscillated by means 35 of a magnet system which acts upon a circular armature plate centrally fastened to the foil. Further characteristic features will appear from the specification.

In the drawing some constructional forms of the invention are shown by way of examples.

Fig. 1 is a section through an amplifier microphone according to the invention.

Fig. 2 is a detail.

Fig. 3 shows a further constructional form of the amplifier according to the invention.

Fig. 4 shows in perspective view a magnet system which is suited for use in a microphone according to the invention.

Fig. 5 is a vertical section on an enlarged scale through still another constructional form of the invention.

Figs. 6 and 7 show also on an enlarged scale a front and a rear view of the inner parts of the amplifier according to Fig. 5.

In a casing 1 made of vulcanized rubber or any other insulating material a magnet system is located, the pot-shaped radially slotted or divided soft iron core 2 of which has a central pole 3 adjacent to which the edge 4 of the outer pole is situated in such a position that only a narrow annular air gap separates the same. My means of a cover 5 the magnet system is kept in its place in the casing or box 1. The casing 1 also contains a diaphragm 6 of a high grade elastical material, preferably phosphor-bronze the thickness of which is only a few hundred parts of a millimetre or thinner. The edges of this foil are soldered to a supporting ring 7 which rests against an abutment 8 in the casing. To the central part 75 of the foil a disc shaped iron armature is soldered which has a thickness of only some tenth part of a millimetre and a diameter of a few millimetres, so that it just covers the air gap of the exciter magnet system aforementioned. On account of the small mass 80 of the oscillating system good damping may be obtained. By means of forcible stretching to be described presently combined with small dimensions the natural frequency of 85 the system may be kept outside the range of the normal voice frequencies. Practically its natural frequency ranges above one thousand oscillations per second. It is important to note that the system practically 90 possesses one natural frequency only because the central part only performs reciprocating oscillations and no formation of nodes will take place on account of the small mass of the foil edge zone.

The forcible stretching of the diaphragm is obtained by pressing the edge 11 of the microphone cell 10 against the diaphragm

6 adjacent to the supporting ring 7. The pressure is effected by means of a cover 12 which is screwed into the casing.

The central part of the microphone cell 5 10 contains a space for the resistance material 13 which is surrounded by a felt ring 14 in such a manner that only the parts of the diaphragm performing the greatest amplitudes will act upon the material. As a 10 contact material preferably very fine granulated carbon is used, which secures a very good effect on account of the great number of contact points.

The very considerable resistance between 15 the diaphragm and the material which otherwise naturally would arise is prevented, because the element in contact with the material consists of metal and not of carbon. To further improve the contact 20 the diaphragm is provided with a coating of gold or platinum, whereby the side facing the granulated carbon always remains clean and a formation of oxides, which alters the resistance, is prevented.

25 The side of the microphone cell lying remote from the diaphragm comprises a carbon plate or a metal plate 15 of a precious metal or a plate provided with a precious metal coating.

30 In spite of the fact that the contacts between metal and carbon usually are regarded as being poor, the effect of the present microphone arrangement is extremely satisfactory, because the resistance 35 at the contact point of the two materials is small and the change of resistance takes place over a proportionately long way between a great number of succeeding small particles, whereby the amplitude of the diaphragm is small in comparison to the length 40 of the path in the granulated carbon.

In order to prevent disturbing elastic reactions from the felt ring 14 this ring is made of such dimensions that it is maintained under pressure when it is located in place. It is also possible to do without the ring 14 in which case the microphone cell 10 is almost filled with granulated carbon as shown in Fig. 2. To prevent a short-circuiting of the effective central parts of the carbon filling through the outer parts of the same which are subjected only to small alterations in pressure and resistance, the conducting counter plate 15 is centrally arranged, so that the outer parts of the carbon filling will not come into action. The same effect may be obtained by applying to the edge of the diaphragm and of the counter plate a coating of varnish.

50 It is further possible to improve the effects of the amplifier by arranging the carbon cell between two diaphragms each of which is operated by a magnet system 2 2' respectively, as shown in Fig. 3. The stretching 55 of the diaphragm is effected in this case in

the following manner. In the casing 1 the diaphragm 6 is first located, its supporting ring 7 resting on a shoulder provided in the casing. On the diaphragm 6 rests a ring 16 which forms the carbon cell and 70 against the other side of which the second diaphragm 6' is placed. The supporting ring 7' of the latter diaphragm is supported by a casing part 17 which is screwed into the casing 1 and in which the second magnet 75 2' is fastened by means of a cover 5'. When screwing the part 17 into its place the diaphragms 6 and 6' are stretched.

As shown in Fig. 4 instead of a pot-shaped soft iron magnet a permanent magnet 18 may be used, the one pole piece 19 of which surrounds the other pole piece 20 in such a manner that also here an annular gap of relatively small diameter faces the armature, 18' denotes the exciting coils for 85 the microphone.

The Figs. 5, 6 and 7 show a further embodiment of the invention, which on account of its small dimensions and its other advantageous properties is very well suited for 90 use for instance for aural telephone devices for persons hard of hearing.

According to this constructional form the apparatus consists of a casing 21 of hard rubber and a metallic cover 22 connected to it by a thread 23 in which cover a magnet system and a microphone controlled by the former are located. This magnet system may have a soft iron core or a permanent magnet core. The system shown is of the latter type. It consists of a ring of steel 24 magnetized in diametral direction as indicated by the letters N and S in Fig. 7. To the south-pole S is rigidly connected a sector-shaped piece 25 of iron at the end 100 of which an iron core 26 is arranged coaxially with the ring 24. To the lower part S of the ring magnet 24 a disc 28 of soft iron is fixed by a spacing piece 27 of non-magnetic material which disc is fixed to the 110 upper part N of the ring by an iron piece 29. The disc 28 is provided with a projecting part 30 and with a radial slot 31 preventing the flow of short-circuit currents. In the plane of the projecting part 30 this disk forms the north pole and the end of the core 26 forms the south-pole of the magnetic system. On the pin 26 is arranged the winding 31 controlling the microphone. The magnet system is inserted into the casing 115 21 and a bushing 32, adapted to lead the winding terminals 33 out of the casing, is guided in a slot 34 of the casing 21.

On the rim of the disc 28 a distance ring 35 of nonmagnetic metal is laid and upon this ring the microphone is arranged. The microphone comprises a diaphragm 35' which is composed of a high grade elasical material preferably phosphor-bronze and of a thickness amounting only to a few-hundred 120 125 130

parts of a millimetre or less. The edge of this foil is soldered to a supporting ring 36 and is contained in an annular casing which rests on the distance ring 35. To the central 5 part of this foil a disc shaped iron armature 37 is soldered, which has a thickness of only some tenth part of a millimetre and a diameter of about 10 millimetres so that it just covers the air gap between the poles 26 and 30 of the magnet system. The foil or diaphragm 35' is kept permanently spanned or stretched by means of a body 38 containing the microphone cell and being provided with an annular edge 39 which is 10 pressed against the foil 35' by means of the inwardly turned edge of casing 40 which clamps together the supporting ring 36 and the edge of the microphone cell 38. In the microphone cell a filling 41 preferably of 15 granulated carbon is used as resistance material and the peripheral parts of the diaphragm are preferably damped by means of a felt ring 42, so that only the central part of the diaphragm, which has the greatest 20 amplitude, comes into action.

In the bottom of the microphone cell 38 an opening is formed into which a cylindrical projection 43 of a metal plate 44 projects in such a manner that it presses with 25 its inner face against the carbon filling 41. This plate and also the entire microphone cell are held in place by the cover 22 of the casing 21. The projection 43 as well as the walls and sides of the microphone cell may 30 partly or completely be covered with a coating of gold or platinum.

The electrical connection of the projection 43 is formed by a metal cap 45 put over the cover 22 at the edge of which a bifurcated 35 tongue 46 is arranged. This tongue straddles a bolt 47 on casing 21. One of the plugs 48 is connected to the bolt 47 and the other plug 48 is connected to diaphragm 35' (connection not shown). This may 40 illustrate how the microphonic relay may be connected for instance to a dry battery.

What I claim as my invention and desire 45 to secure by Letters Patent is:

1. In a microphonic relay a radially 50 stretched metal foil diaphragm, a disc-shaped iron armature centrally located upon the foil, an operating magnet comprising an outer annular pole and an inner pole stud, the inner pole being spaced from the outer pole 55 so that only a narrow annular air gap separates the poles, said armature being of sufficient size to bridge said annular gap.

2. In a microphonic relay a metal foil diaphragm, an iron armature centrally located 60 upon the diaphragm, a pot-shaped exciting magnet comprising an outer annular pole and an inner pin-shaped pole, the inner pole being spaced from the outer pole by a narrow intermediate air gap, said armature be-

ing of sufficient size to bridge said gap, and a 65 casing surrounding the entire device.

3. In a microphonic relay a metal foil diaphragm, an iron armature centrally located upon the diaphragm, a pot-shaped exciting magnet comprising an outer annular pole 70 having a radial slot, and an inner pin-shaped pole, the inner pole being spaced from the outer pole by a narrow intermediate air gap, said armature being of sufficient size to bridge said gap, and a casing surrounding 75 the entire device.

4. In a microphonic relay a metal foil diaphragm, a supporting ring to which the said foil is fastened, an iron armature centrally located upon the same, pole pieces acting 80 upon the armature, a microphone cell closed by said diaphragm, a casing surrounding the entire device and being concentrically located in relation to the said microphone cell and the said diaphragm, an 85 annular shoulder in the casing adapted to hold the said supporting ring and the said diaphragm in fixed relation to the other elements of the amplifier when the said diaphragm and the said supporting ring are 90 pressed against the said seat by means of the microphone cell.

5. In a microphonic relay a metal foil diaphragm, a supporting ring to which the said foil is fastened, an iron armature centrally 95 located upon the same, pole pieces acting upon the armature, a circular microphone cell having an annular rim, said diaphragm having a coating of a precious metal and closing said cell across said annular rim, 100 and a filling of finely granulated carbon enclosed in said cell, a casing surrounding the entire device and being concentrically located in relation to the said microphone cell and the said diaphragm, an annular shoulder 105 in the casing adapted to hold the said supporting ring and the said diaphragm in fixed relation to the other elements of the amplifier when the said diaphragm and the said supporting ring are 110 pressed against the said seat by means of the microphone cell, and means for pressing said cell against said diaphragm.

6. In a microphonic relay a metal foil diaphragm, a supporting ring to which the said foil is fastened, an iron armature centrally located upon the same, pole pieces acting 115 upon the armature, a circular microphone cell having an annular rim, said diaphragm having a coating of a precious metal and closing said cell across said rim and a filling 120 of finely granulated carbon enclosed in the said cell, means for preventing the peripheral parts of the microphone diaphragm in partaking in the oscillations, a casing surrounding the entire device and being concentrically located in relation to the said microphone cell and the said diaphragm, an 125

nular shoulder in said casing adapted to hold the said supporting ring and the said diaphragm in fixed relation to the other elements of the relay when the said diaphragm and the said supporting ring are pressed against the said shoulder by means of the microphone cell, and means for pressing said cell against the diaphragm.

7. In a microphonic relay a metal foil diaphragm, a supporting ring to which the said foil is fastened, an iron armature centrally located upon the same, pole pieces acting upon the armature, a circular microphone cell having an annular rim, said diaphragm having a coating of a precious metal and closing said cell across said rim and a filling of finely granulated carbon enclosed in the said cell, a casing surrounding the entire device and being concentrically located in relation to the said microphone cell and the said diaphragm, an annular shoulder in said casing adapted to hold the said supporting ring and the said diaphragm in fixed relation to the other elements of the relay, when the said diaphragm and the said supporting ring are pressed against the said seat by means of the microphone cell, and covers at both ends of the said casing for holding the different members of the relay together.

8. In a microphonic relay a diaphragm, an iron armature centrally fixed on said diaphragm, a casing forming with said diaphragm a microphone cell; a filling of contact material in said cell, a ring-shaped permanent magnet diametrically magnetized, an iron pin arranged in central axial relation to said magnet, an element magnetically connecting said pin to one of the poles of said magnet, an exciting winding surrounding said pin, an annular pole piece surrounding the free end of said pin in spaced relation to the same, and another element magnetically connecting said pole piece to the other pole of said magnet, said armature being suitably spaced from the pin and said circular pole piece to bridge the gap between said two-elements.

9. In a microphonic relay a metal foil diaphragm, a supporting ring to which the said foil is fastened, an iron armature centrally located upon the same, a ring-shaped diametrically magnetized magnet, a sector-shaped element rigidly fastened to one pole of said ring-shaped magnet and radially arranged in relation to the same, an iron pin disposed in axial alinement with said magnet and being fastened to the inner end of the said sector-shaped element, an exciting coil for the microphone surrounding the said iron pin, a radially slotted soft iron disc arranged in spaced relation to the said ring-shaped magnet and to the said metal foil diaphragm, coaxially with and in parallel to these elements, two distance pieces connecting the said soft iron disc to the said magnet, one distance piece being of non-magnetic material and being arranged adjacent to one pole of the magnet, the other distance piece being of a magnetic material and being arranged adjacent to the other pole of the magnet, a central annular projection on the said soft iron disc, surrounding the free end of the said iron pin to form a gap, a washer separating the said soft iron disc from the said diaphragm supporting ring, a circular body having a central aperture and an annular flange adapted to be pressed against the said diaphragm adjacent to its periphery for stretching the diaphragm, a clamping ring surrounding the peripheries of the diaphragm supporting ring and the said circular body, a metal plate having a central cap which projects through the central aperture in the said circular body and together with the annular flange of the same and the diaphragm serves to form a microphone cell, a peripheral felt ring and a filling of granulated carbon in

one distance piece being of non-magnetic material and being arranged adjacent to one pole of the magnet, the other distance piece being of a magnetic material and being arranged adjacent to the other pole of the magnet, a central annular projection on the said soft iron disc, surrounding the free end of the said iron pin to form a gap, a washer separating the said soft iron disc from the said diaphragm supporting ring, a circular body having a central aperture and an annular flange adapted to be pressed against the said diaphragm adjacent to its periphery for stretching the diaphragm, a clamping ring surrounding the peripheries of the diaphragm supporting ring and the said circular body, a metal plate having a central cap which projects through the central aperture in the said circular body and together with the annular flange of the same and the diaphragm serves to form a microphone cell, a peripheral felt ring and a carbon filling in the said cell and means for holding the several parts of the device together.

10. In a microphonic relay a metal foil diaphragm, a supporting ring to which the said foil is fastened, an iron armature centrally located upon the same, a ring-shaped diametrically magnetized magnet, a sector-shaped element rigidly fastened to one pole of said ring-shaped magnet and radially arranged in relation to the same, an iron pin disposed in axial alinement with said magnet and fastened to the inner end of the said sector-shaped element, an exciting coil for the microphone surrounding the said iron pin, a radially slotted soft iron disc arranged in spaced relation to the said ring-shaped magnet and to the said metal foil diaphragm coaxially with and in parallel to these elements, two distance pieces connecting the said soft iron disc to the said magnet, one distance piece being of non-magnetic material and being arranged adjacent to one pole of the magnet, the other distance piece being of a magnetic material and being arranged adjacent to the other pole of the magnet, a central annular projection on the said soft iron disc, surrounding the free end of the said iron pin to form a gap, a washer separating the said soft iron disc from the said diaphragm supporting ring, a circular body having a central aperture and an annular flange adapted to be pressed against the said diaphragm adjacent to its periphery for stretching the diaphragm, a clamping ring surrounding the peripheries of the diaphragm supporting ring and the said circular body, a metal plate having a central cap which projects through the central aperture in the said circular body and together with the annular flange of the same and the diaphragm serves to form a microphone cell, a peripheral felt ring and a carbon filling in

the said cell, a coating of precious metal on the diaphragm portions and the cap coming into contact with the carbon filling a container element encompassing the said different parts, a threaded holding ring serving to retain the several different parts in the container element, an outer ring for fix-

ing the said holding ring to the said container element and means for connecting the said outer ring to the said containing element. 10

In testimony whereof I affix my signature.

HELMUT SELL.
